(57) **CLAIM**

The ornamental design for a latch, as shown and described.

DESCRIPTION

Cross-reference is made to U.S. Design patent App. Ser. No. 29/585,272 titled "Cooler," filed Nov. 22, 2016, and U.S. Utility patent application Ser. No. 15/819,950 titled "Cooler," filed Nov. 21, 2017, all of which are expressly incorporated herein by reference.

FIG. 1 is a front perspective view of an embodiment of a latch design;

FIG. 2 is a front elevation view of the design of FIG. 1;
FIG. 3 is a rear elevation view of the design of FIG. 1;
FIG. 4 is a left side elevation view of the design of FIG. 1,
the right side elevation being a mirror image of FIG. 4;
FIG. 5 is a top plan view of the design of FIG. 1; and,
FIG. 6 is a bottom plan view of the design of FIG. 1.

The broken lines shown in the figures represent the boundary of the claimed design and portions of the latch that form no part of the claimed design.
